COMBINED TOOTHBRUSH, TOOTHPASTE, AND TUMBLER HOLDER

Melvin O. Maxwell, 3429 S. Sanford,
Stow, Ohio 44724

Filed Oct. 24, 1966, Ser. No. 4,395

Term of patent 14 years

(Cl. D4—3)

FIG. 1

FIG. 3

FIG. 1 is a top plan view of a combined toothbrush, toothpaste, and tumbler holder embodying my new design.

FIG. 2 is a front elevational view thereof.

FIG. 3 is an elevational view taken from one side thereof.

I claim:

The ornamental design for a combined toothbrush, toothpaste, and tumbler holder, as shown.
